SUCTION LINE FOR STORAGE TANKS

John G. Steele, Latrobe, Pa.

Application July 14, 1932, Serial No. 622,528

13 Claims. (Cl. 220—85)

This invention relates to suction lines for storage tanks, and more particularly to a suction line assembly for underground gasoline storage tanks.

As is well known, it is the common practice 5 to place gasoline and other liquid fuel storage tanks beneath the surface of the ground, and to provide dispensing pumps arranged on the surface of the ground connected to the storage tanks by suitable suction lines. Such tanks usually are 10 provided at one end with a filling pipe and at their centers with vent pipes for carrying off evaporated gases, the suction line being arranged at the opposite end of the tank. In the case of larger tanks, two suction lines are provided to 15 permit the dispensing of the fuel from a plurality of pumps.

Such installations are necessary for various reasons, such as the economy in space provided by burying the tanks, as well as the safety in 20 arranging tanks of combustible fuels below the surface of the ground. These installations, however, are subject to a great disadvantage due to the occasional failure of the suction line. It is 25 the common practice to project the suction line downwardly vertically into the tank by employing a depending pipe having a foot valve at its lower end. With the automatic measuring pumps in common use, it is essential that the fuel 30 foot valve operate perfectly, otherwise the fuel will not be properly measured. Regardless of any precautions which may be taken, a certain amount of foreign material finds its way into 35 the tank and sometimes accumulates around the foot valve seats, thus preventing the valve from properly seating.

Measuring pumps are subject to frequent inspections by sealers of weights and measures, and are sealed against use if any inaccuracy in measuring is found. Such inaccuracies are nearly 40 always due to defective operation of the foot valves, and under such conditions it is necessary to excavate the ground around the tank to withdraw the lower end of the suction line from the tank to clean, repair or replace the foot valve. 45 Such a failure in an apparatus of this character is quite expensive due to the cost of excavation and the loss of business to the wholesaler and retailer.

An important object of the present invention 50 is to provide a novel form of suction line assembly for storage tanks which permits the foot valve to be removed and replaced in a few minutes without the necessity for the usual excavation.

A further object is to provide an apparatus 55 of the character referred to which includes the

use of a sleeve extending upwardly from the tank to the surface of the ground and through which the foot valve and its associated pipe may be readily removed.

A further object is to provide a suction line 60 structure of such character as to minimize the collection of foreign material on the foot valve seats, thus rendering the operation of this device more positive and accurately uniform.

A further object is to provide a structure of 65 the character referred to which permits the connection of the vent pipe thereto, thus eliminating the necessity for a separate connection between the vent pipe and the tank.

A further object is to provide a vertical sleeve 70 structure extending from the tank to the surface of the ground and through which the foot valve is adapted to be removed, and to provide means for exhausting the air from the sleeve structure 75 to prevent the presence of the air in the sleeve structure from interfering with the proper accurate operation of the measuring pump.

A further object is to provide a structure of 80 the character referred to having means for collecting sediment to prevent it from flowing downwardly into the foot valve, and to provide a structure of such character as to minimize the agitation 85 of the collected sediment.

Other objects and advantages of the invention 85 will become apparent during the course of the following description.

In the drawings I have shown one embodiment of the invention. In this showing,

Figure 1 is a vertical sectional view through 90 a fuel storage tank showing it embedded in the ground, the suction line and other piping connections, and a portion of the pump, being shown in elevation,

Figure 2 is an enlarged vertical sectional view of 95 the sleeve assembly and associated elements,

Figure 3 is a fragmentary sectional view of the upper end of the sleeve assembly, further enlarged, and showing the air vent screw in open position, and,

Figure 4 is a transverse section on line 4—4 of 100 Figure 2.

Referring to Figure 1, the numeral 10 designates a liquid storage tank shown in the present instance as a gasoline tank, and this tank is of the usual or any desired construction. A filler 105 pipe 11 communicates with one end of the tank and extends from the tank to the surface of the surrounding ground 12. A depending pipe 13 extends from the filler pipe downwardly into the tank to a point near the bottom thereof to mini- 110

imize the generation of gases incident to the agitation of the fuel while the tank is being filled. Ordinarily, the tank is provided centrally thereof with a vent pipe for carrying away generated 5 gases, but the conventional type of vent pipe is eliminated in the present construction in a manner to be referred to.

A casing or sleeve 14 extends from the tank to the surface of the ground and is threaded at its 10 lower end as at 15 for connection with a collar 16 of the usual type secured to the top of the tank. The tank is provided with an opening 17 registering with the lower end of the sleeve 14, as will be apparent.

15 Referring to Figure 2, it will be noted that the sleeve 14 is cylindrical throughout the greater portion of its length, a portion of the lower end of the sleeve being tapered as at 18 to decrease in diameter downwardly. Adjacent the lower end 20 of the cylindrical portion of the sleeve, an internal tapered seat 19 is provided, for a purpose to be described. This seat obviously is arranged a substantial distance above the tank, and beneath the seat, the sleeve 14 is provided with an internally threaded boss 20 to which is connected the inner end of a nipple 21. A union 22 connects the nipple to one end of a vent pipe 23, and this pipe is led to any suitable point for the safe disposal of 25 gases passing therethrough. Obviously the vent pipe communicates with the interior of the tank 30 through the lower end of the casing 14 and the opening 17.

A depending suction pipe 24 extends through the bottom of the casing 14 and into the tank 10 to 35 a point adjacent the bottom thereof, and the lower end of the pipe 24 is provided with any suitable form of foot valve indicated as a whole by the numeral 25. Obviously the foot valve operates as a check valve to maintain the head of fuel in the 40 pipe 24 and the various connections of this pipe, to be described.

A feed pipe 26 is arranged within the sleeve 14 and is provided at its lower end with a circular head 27 which is only sufficiently smaller than 45 the cylindrical portion of the sleeve 14 to provide clearance to permit the pipe 26 to be freely moved upwardly. A valve facing 28 is arranged against the tapered lower face of the head 27, and this head is provided with a depending cylindrical 50 portion 29 with which the facing 28 engages to maintain it in proper position with respect to the head 27. The facing 28 forms, in effect, a seat engageable with the valve seat 19, and is formed of a suitable composition which is resistant to the 55 particular material in the tank 10.

The sleeve 14 is provided with a plurality of internally threaded bosses 30 arranged in a common plane at right angles to the axis of the sleeve 14 and spaced a substantial distance above the 60 head 27. In the present instance, only two of the bosses 30 have been illustrated, one being closed by a plug 31 and the other being shown connected to a nipple 32. This nipple is connected by a union 33 to a pipe 34. The pipe 34, in turn, leads 65 to any conventional type of dispensing pump mechanism 35, usually of the automatic measuring type.

Only one of the bosses 30 is shown as being 70 utilized as a liquid outlet means, but it will be apparent that a dispensing pump may be connected to each of the bosses instead of one of the bosses being closed by the plug 31. It also will be apparent that in the case of larger tanks 10, the 75 sleeve 14 may be provided with additional bosses

30 for connection with additional dispensing pumps.

The upper face of the head 27 is horizontal and is of a size substantially corresponding to the internal diameter of the sleeve 14, only sufficient clearance being provided to permit upward movement of the head 27, as stated. Accordingly, the upper face of the head 27 is adapted to support sediment collecting thereon in a manner to be described, and inasmuch as the nipple 32 is arranged a substantial distance above the head 27, the latter element forms the bottom of a sediment trap or pocket 35'. As will become apparent, the sediment collects during the pumping of the liquid and is prevented from flowing downwardly through the pipe 24, and thus tends to prevent the collection of foreign material on the seats of the foot valve 25.

The upper end of the pipe 24 is threaded in the depending end 29 of the head 27 and communicates with the lower end of the pipe 26, as clearly shown in Figure 2. The pipe 26 is provided with rows of circumferentially spaced openings 36 through which fuel flows into the sleeve 14. It will be apparent that all of the openings 36 are 100 arranged above the level of the nipple 32.

The upper end of the sleeve 14 is offset outwardly as at 37 to provide a shoulder or seat 38. A cap or plug 39 is threaded in the upper end of the sleeve 14 and is provided with an enlarged 105 upper end beneath which is arranged a suitable composition gasket 40 engaging against the seat 38 to provide an air-tight joint. A suitable wrench receiving opening 41 is formed in the upper face of the cap 39. On its lower face the 110 cap 39 carries a boss 42 in which is threaded the upper end of a rigid rod 43. A tapered centering plug 44 is slidable on the lower end of the rod 33 and is provided at its upper end with an annular flange 45 engaging the upper end of the 115 pipe 26. A nut 46 is threaded on the lower end of the rod 43 to support the plug 44 on the rod when the cap 39 is removed, and the nut 46 is normally arranged slightly beneath the plug 44 as shown in Figure 2. A spring 47 of the compression type surrounds the rod 43 between the lower face of the cap 39 and the upper face of the plug 44, and accordingly urges the latter member downwardly.

The upper end of the sleeve 14 is closed to the 125 atmosphere, and means is provided for permitting the escape of air from the upper end of the sleeve 14 when the apparatus is initially operated to prevent the sleeve from acting as an air trap. In this connection, it has been found that meas- 130 using pumps are dependent for their operation on the absence of air in the suction line, and if the upper end of the sleeve 14 is permitted to act as an air trap, the measuring pump cannot accurately function. Referring to Figures 2 and 3, 135 the numeral 48 designates an opening drilled through the bottom of the cap 39 and communicating at its upper end with a somewhat larger opening 49 receiving a screw 50. The upper end of the threaded opening is counter-sunk as at 51 140 to receive the head of the screw so that the latter is normally arranged flush with the upper face of the cap 39, as shown in Figure 2. The screw 50 is drilled axially through its lower end to provide a passage 52 communicating at its upper end with a transverse passage 53 which communicates with the atmosphere when the screw 50 is backed out as suggested in Figure 3. It will be apparent that the opening 53 is closed to communica- 145 150

tion with the atmosphere when the screw 50 is in the normal position shown in Figure 2.

The operation of the apparatus is as follows:

The storage tank is filled in the usual manner 5 through the pipes 11 and 13, the latter having its lower end arranged in the fuel to minimize the generation of gas due to the agitation of the fuel as the tank is being filled. The tank is vented to the atmosphere through the vent pipe 23, and 10 this pipe communicates with the tank through the bottom of the sleeve 14 and the opening 17, the structure referred to permitting the elimination of the added vent pipe connection which ordinarily is necessary.

15 The measuring pump is operated in the usual manner to dispense the fuel, the various elements between the foot valve 25 and the pump constituting a suction line through which the fuel flows to the pump to be dispensed thereby. As previously stated, the operation of the measuring pump is dependent upon the suction line being completely filled with liquid, and accordingly the initial operation of the apparatus requires the removal of the air from the upper end of the 25 sleeve 14. Accordingly the pump is initially operated to fill the suction line, whereupon the screw 50 is backed out a sufficient extent to afford communication between the sleeve 14 and the atmosphere through the port 48, opening 49, and 30 passages 52 and 53. The accumulated head of liquid in the pump flows back through the pipe 34 into the casing 14 until all of the air has been exhausted from the sleeve 14, and when the fuel starts to flow out of the opening 53, the screw 50 35 is then tightened to cut off communication between the sleeve 14 and the atmosphere. The apparatus is then ready for normal operation.

Upon the creation of a suction by the pumping means, the atmospheric pressure present in the 40 tank 10 causes the fuel to flow upwardly through the pipes 24 and 26, and the fuel is discharged from the latter pipe into the sleeve 14 through the openings 36. From the sleeve 14, the fuel flows to the pump through the nipple 32 and pipe 45 34, and is dispensed from the pump 35 in the usual manner. Foreign material is always present in the fuel to a certain extent regardless of any precaution which may be taken and the pocket 35' collects the foreign material. Upon 50 the completion of a pumping operation, the pocket 35' holds the sediment and thus prevents it from flowing back into the tank through the foot valve. As previously stated, the lowermost opening 36 is arranged above the nipple 32, thus preventing sediment from being drawn directly into 55 the nipple 32 and permitting sediment to settle in the pocket 35'. Moreover this construction prevents any downward flow of the sediment from the pocket 35' into the pipes 26 and 24. It 60 is the collection of sediment in the foot valve seats which usually affects the operation of these elements, and the trapping of the sediment tends to protect the foot valve seats, thus rendering it seldom necessary to remove them for cleaning, 65 repair or replacement.

With the structures commonly employed, it is necessary to excavate the ground to gain access to the foot valves when trouble occurs with these elements. In the present instance, such excavation 70 is unnecessary. When it is desired to remove the foot valve, the cap 39 is removed together with the plug 44 and associated elements, whereupon the pipe 26 may be drawn upwardly for removal through the upper end of the sleeve 75 14, together with the head 27, seat 28, pipe 24

and foot valve 25. In this connection, it will be noted that the opening beneath the seat 19 is at least as large in diameter as the foot valve to permit its removal therethrough. Thus it will be apparent that the foot valve readily may be removed and any desired operation performed thereon, whereupon it may be replaced and the apparatus again operated in the normal manner. The entire operation of removing and replacing the foot valve does not require over fifteen minutes, and accordingly the trouble and expense of excavating is eliminated, together with the loss of business to the wholesaler and retailer incident to the time lost in excavating.

As previously stated the upper face of the head 27 is arranged a substantial distance below the nipple 32 and the lowermost opening 36, and thus forms the bottom of a sediment trap. After each pumping operation, any sediment remaining in the sleeve 14 settles in the sediment trap, and thus is prevented from flowing downwardly through the pipe 24 to interfere with the operation of the foot valve. In view of the fact that the diameter of the head 27 is substantially equal to the internal diameter of the sleeve 14, it will be apparent that the head acts as a plunger in the sleeve, and upon each removal of the foot valve in the manner described, the head 27 carries upwardly with it any sediment which may have collected thereon, whereby such sediment may be removed. Before replacing the foot valve, the seats 19 and 28 are preferably wiped clean to insure perfect seating between these elements.

It will be obvious that the spring 47 normally acts to retain the seats 19 and 28 in firm engagement, thus preventing any leakage of liquid back into the tank past the seats referred to, and the closing of the valves of the pump prevents the liquid in the sleeve 14 from flowing back into the tank through the pipe 24. Thus it will be apparent that a pressure head is retained above the head 27 to assist the spring 47 in maintaining firm engagement between the seats 19 and 28. As previously stated, the nut 46 is normally arranged slightly below the plug 44, thus permitting the spring 47 to transmit its full force to the upper end of the pipe 26 to maintain the firm engagement between the seats 19 and 28. In assembling the device, the foot valve and the elements connected thereto are first inserted, whereupon the cap 39 is placed in position above the end of the sleeve 14 with the lower end of the plug 44 in the upper end of the pipe 26. When the cap 39 is then screwed downwardly the plug 44 serves to properly center the pipe 26, thus 130 properly positioning the seats 19 and 28 with respect to each other.

In addition to serving as means for filling the tank and as means forming a part of the sediment trap or pocket 35' the sleeve 14 serves to 135 provide a pressure head of liquid, thus adding additional weight tending to hold the foot valves on their seats, and therefore prevents leakage. The prevention of leakage at the point indicated 140 is essential to the proper operation of the pump, and in the usual constructions, the sleeve 14 contains approximately three gallons of gasoline, and accordingly it will be apparent that a substantial pressure head is maintained.

It is to be understood that the form of the invention herewith shown and described is to be taken as a preferred example of the same and that various changes in the shape, size and arrangement of parts may be resorted to without 145

departing from the spirit of the invention or the scope of the subjoined claims.

I claim:

1. In a suction line assembly for storage tanks, a vertical casing having an open lower end secured to the top of the tank and communicating with the interior thereof, a pipe projecting downwardly into the tank through the lower end of said casing and having a foot valve at its lower end, said pipe having its upper end projecting upwardly into said casing a substantial distance above the lower end thereof, a seat formed in said casing near its lower end, a seat formed on said pipe and engaging the seat in said casing to form a leak-proof joint, said pipe being spaced a substantial distance from said casing throughout the portion of the pipe above said last named seat, an outlet pipe communicating with the casing a substantial distance above said seats, said first named pipe communicating with said casing wholly above said outlet pipe, and a member closing and sealing the upper end of said casing and removable to permit withdrawal of said first named pipe through the upper end of said casing.
2. In a suction line assembly for storage tanks, a vertical casing having an open lower end secured to the top of the tank and communicating with the interior thereof, a pipe projecting downwardly into the tank through the lower end of said casing and having a foot valve at its lower end, said pipe having its upper end projecting upwardly into said casing a substantial distance above the lower end thereof, a seat formed in said casing near its lower end, a head carried by said pipe and provided with a seat on its lower face engaging said first named seat to form a leak-proof joint, said head corresponding in shape and size to the interior of said casing and provided with a horizontal upper face, said casing being of substantially uniform cross-sectional shape and size from said head to the upper end of said casing and spaced from the portion of said pipe above said head, an outlet pipe communicating with the casing a substantial distance above said head, said first named pipe communicating with said casing wholly above said outlet pipe, and a member closing and sealing the upper end of said casing and removable to permit withdrawal of said first named pipe through the upper end of said casing.
3. In a suction line assembly for storage tanks, a vertical casing having an open lower end secured to the top of the tank and communicating with the interior thereof, a pipe projecting downwardly into the tank through the lower end of said casing and having a foot valve at its lower end, said pipe having its upper end projecting upwardly into said casing a substantial distance above the lower end thereof, a seat formed in said casing near its lower end, a head formed on said pipe and having a seat formed on its lower face engageable with said first named seat to form a leak-proof joint, said head being circular and having a horizontal upper face, said casing being cylindrical and of substantially greater diameter than said pipe from said head to the upper end of said casing and being of an internal diameter substantially equal to the diameter of said head, an outlet pipe communicating with said casing a substantial distance above said head, said first named pipe being provided with a plurality of openings communicating with said casing, the lowermost opening being arranged wholly above said outlet pipe, and a member closing and sealing the upper end of said

casing and removable to permit withdrawal of said first named pipe through the upper end of said casing.

4. In a suction line assembly for storage tanks, a vertical casing secured at its lower end to the top of the tank and having open ends the lower of which communicates with the tank, a pipe projecting downwardly into the tank through the lower end of said casing and having a foot valve at its lower end, an internal annular seat formed in the casing, a head carried by the pipe and having a seat cooperating with said first named seat to form a leak-proof joint therewith, the upper face of said head being substantially horizontal and of a diameter substantially equal to the internal diameter of said casing, said pipe communicating with said casing at a point spaced above said head, and a member closing and sealing the upper end of said casing and removable to permit withdrawal of said pipe through the upper end of said casing, said casing having an outlet opening spaced above said head.

5. In a suction line assembly for storage tanks, a vertical casing secured at its lower end to the top of the tank and having open ends the lower of which communicates with the tank, a pipe projecting downwardly into the tank through the lower end of said casing and having a foot valve at its lower end, an internal annular seat formed in the casing, a head carried by the pipe and having a seat cooperating with said first named seat to form a leak-proof joint therewith, the upper face of said head being substantially horizontal and of a diameter substantially equal to the internal diameter of said casing, said pipe communicating with said casing at a point spaced above said head, and a member closing and sealing the upper end of said casing and removable to permit withdrawal of said pipe through the upper end of said casing, said casing having an outlet opening spaced above said head.

6. Apparatus constructed in accordance with claim 5 wherein the seat in said casing is arranged at a point spaced above the lower end of said casing, and a vent pipe communicating with said casing beneath said seats.

7. In a suction line assembly for storage tanks, a vertical casing secured at its lower end to the top of the tank and having open ends the lower of which communicates with the tank, a pipe having its upper end arranged in said casing and its lower end projecting downwardly into the tank through the lower end of said casing and having a foot valve at its lower end, an internal annular seat formed in the casing, a head carried by the pipe and having a seat cooperating with said first named seat to form a leak-proof joint therewith, the upper face of said head being substantially horizontal and of a diameter substantially equal to the internal diameter of said casing, said pipe communicating with said casing at a point spaced above said head, a closure member sealing the upper end of said casing and removable to permit withdrawal of said pipe through the upper end of said casing, and a member carried by said closure member and engaging the upper end of said pipe to center it with respect to said seats, said casing having an outlet opening arranged above the upper face of said head.

8. Apparatus constructed in accordance with claim 7 wherein said centering member comprises a plug engageable in the upper end of said pipe and provided with an upper annular flange contacting with the upper extremity of said pipe, and spring means urging said plug downwardly.

9. Apparatus constructed in accordance with claim 7 wherein said centering member comprises a rigid rod depending from said closure member, and a slidable plug mounted on said rod and engageable in the upper end of said pipe, said plug being provided with an upper annular flange contacting with the upper extremity of said pipe, and spring means surrounding said rod and urging said plug downwardly. 5 80
10. Apparatus constructed in accordance with claim 7 wherein the lower end of said casing is of greater diameter than said pipe and communicates with the tank, said seats being arranged a substantial distance above the lower extremity of said casing, and a vent pipe communicating with said casing beneath said seats. 10 85
11. In a suction line assembly for storage tanks, a vertical casing secured at its lower end to the top of the tank and having open ends the lower 20 90
- 20 of which communicates with said tank, a pipe having its upper end arranged in said casing and its lower end projecting downwardly into the tank through the lower end of said casing and having a foot valve at its lower end, said casing being of substantially greater diameter 25 than said pipe, an internal annular seat formed in the casing near its lower end, a head carried by said pipe and having a seat therebeneath cooperating with said first named seat to form a leak-proof joint, the upper face of said head being substantially horizontal and of a diameter substantially equal to the internal diameter of 30 100
- 30 said casing, said pipe extending a substantial distance above said head and provided with openings the lowermost of which is spaced a substan- 35 105
12. Apparatus constructed in accordance with claim 11 provided with means for maintaining said seats in operative engagement comprising a vertically slidable plug engaging in the upper end of said pipe and having an upper annular flange contacting with the upper extremity of the pipe, and a compression spring urging said plug downwardly. 110
13. In a suction line assembly for storage tanks, a vertical casing secured at its lower end to the top of the tank and having open ends the lower 20 115
- 20 of which communicates with the tank, a pipe projecting downwardly into the tank through the lower end of said casing and having a foot valve at its lower end, the upper end of said pipe communicating with said casing, seats formed in said casing and on said pipe cooperating to form a leak-proof joint, an outlet pipe connected to the casing above said seats, a member closing and sealing the upper end of said casing and removable to permit withdrawal 115 120
- 120 of said first named pipe through the upper end of said casing, and normally sealed means operable for venting the upper end of said casing to the atmosphere. 125
